Primary Examiner — Michael A Pratt*(74) Attorney, Agent, or Firm* — Baker & Hostetler LLP**CLAIM**

The ornamental design for a fletch holder for a crossbow bolt, as shown and described.

DESCRIPTION

FIG. 1 is a top view of a fletch holder for a crossbow bolt showing the claimed new design;

FIG. 2 is a bottom view thereof;

FIG. 3 is a side view thereof;

FIG. 4 is a front view thereof; and,

FIG. 5 is a rear view thereof.

The broken lines in FIGS. 1-5 showing fletchings—also called vanes or feathers—and nock, and/or portions thereof, in association with the claimed design are included for purposes of illustrating environment and form no part of the claimed design.

The claimed fletch holder for a crossbow bolt is used for capturing and holding fletchings in proper alignment and is configured for affixation to the shaft of the crossbow bolt.
